UNITED STATES PATENT OFFICE.

ANTHONY D. COSTER, OF MADISON, WISCONSIN.

BUILT-UP RAILROAD-TIE.

1,101,412.

Specification of Letters Patent. Patented June 23, 1914.

Application filed July 23, 1913. Serial No. 780,811.

To all whom it may concern:

Be it known that I, ANTHONY D. COSTER, a citizen of the United States, residing at Madison, in the county of Dane and State 5 of Wisconsin, have invented certain new and useful Improvements in Built-Up Railroad-Ties, of which the following is a specification.

My present invention relates to railroad ties and more particularly to that class 10 wherein the tie is composed of a plurality of coacting parts adapted to be held rigid one with respect to the other for the purpose of retaining the rails in place upon the road-bed.

15 The principal object of my invention is to provide a tie of the character described which will rigidly hold the rails in spaced relation to each other, a predetermined distance, without the use of spikes or similar 20 devices.

Further objects of my invention are to provide a tie which will prevent longitudinal movement of the rail upon the road-bed; one which can be manufactured at a low 25 cost and is capable of being dismembered when it is desired to alter the layout of any system; and, one which can be assembled, requiring no skilled labor when so doing.

Other objects of the invention will appear 30 in the following detailed description taken in connection with the accompanying drawing, forming a part of this specification, and in which drawing:

Figure 1 is a plan view of ties constructed 35 according to my invention, the rails rigidly spaced thereby being shown partially in section taken longitudinally of the web. Fig. 2 is a sectional view on the line 2—2 of Fig. 1. Fig. 3 is a sectional view on the line 3—3 40 of Fig. 1. Fig. 4 is a perspective view of the base member of one of the ties. Fig. 5 is a similar view showing a coacting member received in one of the ways of said base member. Fig. 6 is a fragmentary perspective view of a rail showing an aperture provided for the reception of a tongue on the base member to prevent longitudinal movement of the rail. Fig. 7 is a perspective view of a wedge-member used in connection 45 with the tie. Fig. 8 is a perspective view showing a modified form of base member, similar to that disclosed in Fig. 4. Fig. 9 is a view similar to Fig. 5 showing the coacting member for the base disclosed in Fig. 8. Fig. 10 is a bottom plan view of the end portion of the base member disclosed in Fig. 4.

In the drawing, where similar characters refer to similar parts, A designates a base member adapted to engage the material making up the road-bed and may be constructed of any suitable dense material, such as cement or metal. It is provided with a longitudinally extending way 11 open at its upper portion, and adjacent its ends has transversely extending ways 12, open to said way 11, for the reception of rails 13'. The ways 12 are at their upper ends, of such a size as to permit the base of the rail to be positioned extending through the ways with one of the base flanges extending into a recess 13 at the bottom of the way. By reference to Fig. 2 of the drawing it is to be noted that these recesses 13 are disposed open to the same sides of ways 12, so that the rail may be forced to engage with that wall of the way adjacent the recess. 75

Fitting into the longitudinally extending way 11 is a retaining member B, having transverse ways 14 for the reception of the rails. The upper portions of ways 11 are 80 adapted to be aligned with the upper portions of ways 12, in order to place the rail and the ways 14 have recesses 15, serving a similar purpose to that of ways 13, but are disposed to receive the opposite flange of 85 the rail. As a suitable means for driving the retaining member B in contact with the rail, and retaining said member B rigid with member A, I provide wedge-shaped slots 16 in the latter and a similar slot 17 90 in member B to be aligned with slots 16 when the lower flanges of the rails are positioned in recesses 13 and 15. A wedge 18 may be driven into slots 16 and 17 to facilitate this retaining of parts. 95

When adjoining rails are in position above one of the ties, I prefer to provide extensions 19 above recesses 13 so that the rail cannot be let down from the top of the member A but must be moved longitudinally 100 into the way 12. In such an instance, the rail 13, adjacent its end, is provided with an aperture 20 into which the said extension 19 may project and thus prevent the rail from moving longitudinally upon the 105 road-bed. It is also necessary to provide a recess 21 in member B opposite from recess 15 in order to permit the rail to be moved into operative relation to the tie, laterally thereof. 110

When the tie is mounted upon a bridge or trestle, it is provided with a plurality of

elongated slots 22 formed in the base member A, and disposed in spaced apart relation to each other longitudinally of said member. The member B is provided with a plurality of apertures 23 so disposed as to open to apertures 22. The apertures 22 and 23 receive the stems of bolts, not shown in the drawings, whereby the tie structure may be made rigid with members of the bridge or trestle. The elongated slots 22 permit movement of one of the tie members with respect to the other for the purpose of removing or placing a rail.

When laying the track, the base member 15 is first rigidly positioned, as by being embedded into the material making up the road-bed. The retaining member B is then placed in the way 11 and the ways 14 and 19 brought into alignment so that a rail, intermediate its ends, may be let down in place. When all is in readiness for the rail to be rigidly positioned with respect to the tie structure, the retaining member B is moved so that one of the lower flanges of 25 the rail will fit into its recess 15, while the other lower flange is positioned in the recesses 13. This may be accomplished by driving the wedge member 18 into the apertures 16 and 17.

30 When adjoining rails are to be supported by a tie structure, the members A and B are assembled one with respect to the other so that the entire tie structure may be moved into operative relation to the rail, or the rail 35 itself moved into operative relation to the tie structure as hereinbefore described, the object in view being to align the extensions with the apertures 20 in the rails. The member B is then moved, as hereinbefore described, as through wedge member 18.

Changes in details may be made without departing from the spirit or scope of my invention; but,

I claim:

45 1. A built-up railroad tie comprising in combination a base member having means for preventing lateral movement of the rail in one direction, a retaining member guided by said base member and adapted to engage 50 the rail to prevent lateral movement in the other direction, rails having apertures and tongues formed on said base for engaging said apertures with said rails for preventing upward and longitudinal movement of said 55 rails, for the purpose set forth.

2. A built up railroad tie comprising in combination, a base member having ways for receiving the rails and preventing move-

ment thereof laterally in one direction, and elongated slots disposed longitudinally of 60 the base member; a retaining member guided by said base member and adapted to engage the rails to prevent movement thereof laterally in the other direction, said retainer member having vertically disposed apertures 65 registering with said elongated slots in said base member; and, means for holding said retaining member rigid with said base member.

3. In a built up railroad tie, the combination of a base member having a longitudinally extending way and aligned transverse ways for rails, leading to said first mentioned way, said second mentioned ways having recesses open at one side thereof for the reception of the base flanges at one side of the rails and a tongue above each of said recesses; two rails each having an aperture to receive the tongue in the respective way the rail extends through; a retaining member guided in the said first mentioned way of said base member and having a way for the reception of the adjacent ends of said rails; said way in said retaining member having a recess for the reception of the base 85 flanges of said rails at the other side thereof; and, means for holding the said retaining member rigid with said base member, substantially as and for the purpose set forth. 90

4. In a built up railroad tie the combination of a base member having a longitudinally extending way and aligned transverse ways for the rails leading to said first mentioned way, said second mentioned ways having oppositely disposed recesses with tongues above the recesses at one side of the said ways; two rails each having an aperture to receive the tongue in the respective way the rail extends through; a retaining member guided in said first mentioned way of said base member and having a way for the reception of the adjacent ends of said rails, said ways in said retaining member having a recess for the reception of the base 105 flanges of said rails at the other side thereof; and, means for holding said retaining member rigid with said base member, substantially as and for the purpose set forth. 95

In testimony whereof I affix my signature 110 in presence of two witnesses.

ANTHONY D. COSTER.
